UNITED STATES PATENT OFFICE

115,029

DESIGN FOR A WELDING GUN

Meril L. Eckman, Cleveland, Ohio, assignor to The
American Coach and Body Company, Cleveland,
Ohio, a corporation of Ohio

Application March 9, 1939, Serial No. 83,481

Term of patent 14 years

To all whom it may concern:

Be it known that I, Meril L. Eckman, a citizen of the United States residing at 952 Cambridge Road, Cleveland, in the county of Cuyahoga and State of Ohio, have invented a new, original, and ornamental Design for a Welding Gun, of which the following is a specification, reference being had to the accompanying drawings, forming a part thereof.

Fig. 1 is a side elevational view of a welding

gun embodying my new design; Fig. 2 is a top plan view thereof, and Fig. 3 is a side elevational view opposite from that shown in Fig. 1.

The dominant features of my design reside in the portions shown in full lines.

I claim:

The ornamental design for a welding gun, as shown and described.

MERIL L. ECKMAN.
